HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed April 27, 1926. Serial No. 104,993.

My invention relates to railway traffic controlling apparatus, and particularly to apparatus of the type comprising train carried governing means controlled by energy received from the trackway. More particularly the present invention relates to the train carried portion of such apparatus.

The present case is a continuation in part of my co-pending application, Serial No. 10 25750, for railway traffic controlling apparatus, filed April 25, 1925, in so far as the subject matter common to the two is concerned.

I will describe one form and arrangement 15 of railway traffic controlling apparatus embodying my invention, and will then point out the novel features thereof in claims.

In the accompanying drawings, Fig. 1 is a view partly diagrammatic and partly in section, 20 showing one form of train carried governing means embodying my invention. Fig. 2 is a diagrammatic view showing one form of trackway apparatus suitable for co-operation with the train carried governing means 25 illustrated in Fig. 1.

Similar reference characters refer to similar parts in both views.

Referring first to Fig. 2, the reference characters 1 and 1^a designate the track rails 30 of a stretch of railway track over which traffic normally moves in the direction indicated by the arrow. These track rails are divided, by means of insulated joints 2, into a plurality of successive track sections A—B, 35 B—C, etc. Each track section is provided with a source of track circuit current, such as a track battery 7, connected across the rails adjacent the exit end of the section. Each track section is also provided with a 40 track relay, designated by the reference character R with an exponent corresponding to the location, and connected across the rails adjacent the entrance end of the section.

Means are also provided for supplying the 45 rails of each section with alternating train controlling current which flows through the rails of the section in series. The immediate source of train controlling current for each track section is a track transformer 50 designated by the reference character T with an exponent corresponding to the location and having a secondary 8 connected across the rails of the associated section in series with the track battery 7. The primary 9 of

each track transformer T is supplied with 55 alternating current over a front contact 11 of the adjacent track relay R from line wires 10 and 10^a. Line wires 10 and 10^a are constantly supplied with alternating current from a suitable source such as an alternator 60 M. It will therefore be plain that each track section is supplied with alternating train controlling current when the section next in advance is unoccupied, but not when such section in advance is occupied.

As shown in the drawing, the section to the right of point C is occupied by a train indicated diagrammatically at V^a. Relay R^c is therefore de-energized, interrupting, at 70 front contact 11 thereof, the circuit for primary 9 of track transformer T^c. Section B—C is therefore supplied with track circuit current but not with alternating train controlling current. Relay R^b is therefore 75 energized and section A—B is supplied with both track circuit current and train controlling current. Similarly, relay R^a is energized and track circuit current and train controlling current are both supplied to the rails of the section to the left of point A. 80

The section to the left of point A is occupied by a train V provided with governing means embodying my invention. Referring now also to Fig. 1 the train carried governing means is controlled from the trackway through the medium of pick-up apparatus comprising two magnetizable cores 12 and 12^a carried on the train V in advance of the front axle 15 and located in inductive relation with the two track rails 1 and 1^a respectively. Core 12 is provided with a winding 13 and core 12^a is provided with a similar winding 13^a, the two windings 13 and 13^a being connected in series so that the voltages induced in the windings by alternating 90 currents flowing in opposite directions in the two track rails at an instant are additive. The windings 13 and 13^a are connected, preferably through an amplifier 14, with winding 18 of an application valve D which is arranged to control the brakes in accordance with the energization or de-energization of winding 18 as will be explained in detail hereinafter.

As the train V proceeds through the 105 stretch of track shown in Fig. 2 valve D will be energized until the train enters section B—C, at which point the interruption of

train controlling current will cause winding 18 of valve D to become de-energized. The winding will remain in its de-energized condition as the train proceeds through section 5 B-C and will also be de-energized in the occupied section to the right of point C.

The train carried governing means comprises the usual automatic brake application mechanism, and also comprises automatic 10 means as well as manual means for actuating this mechanism. The reference character 3 designates the brake pipe which is normally supplied with fluid pressure, usually air, from a suitable source not shown 15 in the drawing, through pipe 6, a reduction valve S, a supply pipe 6^a, a feed valve 47, and an engineman's brake valve P. Pipe 3 controls apparatus which is arranged to apply the brakes when the pressure in this 20 pipe is reduced. The engineman's brake valve P comprises a valve body 38 containing a rotary valve 39 controlled by a manually operable handle 41. The valve body 38 is provided with a cylinder 42 containing 25 an equalizing valve 43. The valve body 38 also contains a port 101 which normally connects pipe 49 with brake pipe 3 but which blanks pipe 49 when the engineman's brake valve is in the service or lap position. 30 Another pipe 91 is controlled by the rotary valve 39 to be vented to atmosphere through port 50 when the valve handle 41 is moved to the release or running position, but to be blanked for other positions of the valve. 35 The reduction valve S comprises a cylinder divided into two chambers 102 and 103 by means of a reciprocable piston 104. The piston 104 is provided with a restricted orifice 105 connecting chambers 102 and 103 40 and is constantly urged to the right-hand or normal position by a spring 106. Air pressure is constantly supplied to chamber 102 through pipe 6. Chamber 103 is at times connected with atmosphere through a 45 pipe 4 as will be explained hereinafter. When pipe 4 is blanked, air pressure leaking through port 105 to chamber 103 from chamber 102 maintains equal pressures on the two sides of piston 104. The combined 50 force exerted by the spring 106 and the pressure in chamber 103 then holds piston 104 in its normal position. When pipe 4 is connected with atmosphere however, the pressure in chamber 103 is reduced and 55 piston 104 is moved, by pressure in chamber 102, into its left-hand or reverse position. Piston 104 controls a slide valve 115 which is arranged to cause a service application of the brakes when the piston moves to its 60 reverse position as will be described in detail hereinafter.

Pipe 4 is controlled in part by valve D which is in turn controlled by traffic conditions, as already described in connection 65 with Fig. 2.

The valve D comprises a valve body 16 containing a piston 19 biased to its upper position by a spring 20. The piston 19 carries a stem 17 terminating in an armature 17^a. The winding 18 is arranged when 70 energized to draw armature 17^a downwardly, thereby moving piston 19 against the bias exerted by spring 20 into a lower position in which pipe 21 is disconnected from pipe 22. When winding 18 is de-energized the piston 19 is allowed to return to its upper position and pipe 22 is then connected with pipe 21. 75

The reference character L designates, in general, a centrifuge comprising a rotating block 28^a operatively connected with a wheel of the train and arranged to rotate at a speed which varies in accordance with the speed of the train. Two weighted levers 31 are pivotally mounted to rotate 80 with block 28^a and to control the position of a shaft 28. An increase in the speed of the train causes levers 31 to move outwardly due to centrifugal force, thereby urging shaft 28 to the left against the bias of a spring 29. The amount of this motion depends upon the speed of the train and the shaft 28 therefore has one and only one longitudinal position for a given train speed. 95

The shaft 28 controls a pin valve E comprising a valve body 24 which is provided with a chamber 25 and a stem 27 normally biased to a closed position by a spring 26. When the speed of the train exceeds a predetermined maximum, shaft 28 engages stem 27 and vents chamber 25 to atmosphere. Chamber 25 is constantly connected with pipe 21. 100

Pipe 4 is normally connected, through a cut-out valve H, as will be explained hereinafter, with pipe 22, and it therefore follows that when magnet 18 of valve D is energized, pipe 4 is disconnected from pin valve E so that this pipe will be blanked, no matter what the speed of the train; but when winding 18 is de-energized, allowing valve D to open, pipe 4 is connected with pipe 21 and chamber 25 of valve E. If, under these conditions, the speed of the train exceeds the predetermined maximum required for the opening of valve E, pipe 4 will be vented to atmosphere and valve S will be reversed. 105

The reference character K designates a relay valve comprising a valve body 67 containing a chamber 68 constantly connected with a vent pipe 44. Chamber 68 contains a flexible diaphragm 69. A plunger 70, controlled by diaphragm 69, is normally urged to its upper position by a spring 71. This plunger controls a valve 72 biased to its upper position by spring 73. When valve 72 is in its upper position pipe 74 is connected with atmosphere through 110 115 120 125 130

port 67^a and is disconnected from pipe 6, but when pressure is admitted to chamber 68, diaphragm 69 and plunger 70 are moved downwardly, so that valve 72 is reversed whereby pipe 74 is disconnected from atmosphere and is connected with pipe 6.

The reference character J designates a repeater valve comprising a cylinder divided into a left-hand chamber 86 and a right-hand chamber 88 by a piston 87. Air pressure is constantly supplied to chamber 86 from pipe 6 and normally holds the piston 87 in its right-hand position against the bias of a spring 89. Pressure is at times supplied to chamber 88 and when this occurs the combined effect of this pressure and the force exerted by spring 89 moves piston 87 to its extreme left-hand position. A slide valve 90, co-operating with certain ports in the wall of chamber 86, is operated by piston 87.

The cut-out valve H referred to above comprises a valve body 32 provided with a cylinder which is divided into an upper chamber 34 and a lower chamber 35 by a flexible diaphragm 33. A plunger 36 is operated by diaphragm 33 and this plunger in turn operates a valve 51. A spring 53 is arranged to urge valve 51 downwardly, permitting communication between pipe 4 and pipe 22. When chamber 35 is supplied with air pressure, plunger 36 is moved upwardly, lifting valve 51 to disconnect pipe 4 from pipe 22.

The differential valve G comprises a valve body 57 having a cylinder which is divided into an upper chamber 58 and a lower chamber 59 by a flexible diaphragm 55. A plunger 56 is controlled by diaphragm 55 and this plunger in turn operates a valve 61. A spring 64 constantly urges valve 61 downwardly. Chamber 58 beneath diaphragm 59 is constantly connected with a reservoir 60 and pipe 49, which pipe is controlled, as already described, by valve P. The chamber 58 is constantly connected with brake pipe 3. The operation of valve G will be described hereinafter, but it should here be stated that when plunger 56 is in its lower position pipe 62 is connected with atmosphere through port 65 and a restricted orifice 66, but that when the plunger is moved to its upper position pipe 62 is disconnected from atmosphere and is connected with brake pipe 3 through flutes in the stem of valve 61 and plunger 56.

As shown in the drawing, all of the parts are in their normal positions, that is, the positions which these parts occupy when the valve D is actuated by alternating train controlling current received from the trackway, and when the engineman's brake valve is in the running position. Under these conditions valve S is in its normal position and air flows from the pipe 6, through valve S,

pipe 6^a, and port 48 of valve P to the brake pipe 3 and also through port 100 of valve P, pipe 110, port 109 in valve S, and pipe 108 to the equalizing reservoir 45 and thence to the cylinder 42 above the equalizing valve 43. The lower side of equalizing valve 43 is constantly connected with brake pipe 3. Equalizing valve 43 is therefore closed and so there is no pressure in pipe 44, this pipe being connected with atmosphere through a restricted orifice 98. Plunger 70 of valve K is in its upper position and pipe 74 is connected to atmosphere through this valve. The reservoir 82 is connected with atmosphere through pipe 91 and port 50 of brake valve P. Chamber 35 beneath diaphragm 33 of valve H is connected with atmosphere through pipe 54, port 92 of valve J, pipe 114, port 113 of valve S, pipe 84, restricted orifice 99, pipe 74, and orifice 67^a of valve K so that plunger 36 of valve H is in its lower position and pipe 4 is connected with pipe 22. Valve D being energized, pipe 22 is disconnected from pipe 21 and so the position of valve E could have no effect upon the position of valve S even though valve H should connect pipe 4 with pipe 22. With the train at rest, however, shaft 28 of centrifuge L occupies its right-hand position so that valve E is closed.

Chamber 58 above diaphragm 55 of valve G is connected directly to brake pipe 3 as already stated. Chamber 59 beneath this diaphragm and reservoir 60 are now connected, by means of pipe 49 and port 101 of brake valve P, with brake pipe 3. The pressures on the upper and lower sides of diaphragm 55 are therefore equal and plunger 56 occupies its lower position and spring 64 holds valve 61 in its lower position so that pipe 62 is connected with atmosphere through port 66 in valve G. Reservoir 96 and chamber 88 of valve J are therefore subjected to atmospheric pressure through pipe 62, and piston 87 of this valve is held in its right-hand position, against the bias exerted by spring 89, by air pressure supplied to chamber 86 from supply pipe 6. It will be plain that with the apparatus in this condition the train is permitted to proceed without the possibility of an automatic application of the brakes.

I will now assume that magnet 18 of valve D becomes de-energized, as by the entrance of train V into section B-C. Piston 19 of valve D is then moved upwardly by spring 20 to connect pipe 21 with pipe 22. The rest of the apparatus is unaffected. Pipe 4 is now connected with valve E through valves H and D, and if the speed of the train exceeds the predetermined speed limit at which centrifuge L will open valve E, pipe 4 will be vented to atmosphere and reduction valve S will reverse to cause an

automatic application of the brakes as will appear hereinafter. It should be pointed out that should valve D become de-energized when the train is proceeding at speeds 5 below the speed limit imposed by valve E, de-energization of valve D will not cause an automatic application of the brakes.

If the engineman operates valve P to cause a manual brake application prior to the de-10 energization of valve D an automatic application of the brakes due to opening of valve E will be prevented as I will now explain. When handle 41 of valve P is moved to the service, or brake applying position, 15 brake pipe 3 is disconnected from pipe 6 and pipe 110 is blanked. At the same time equalizing reservoir 45 and chamber 42 above valve 43 are connected with atmosphere through the usual restricted preliminary 20 port 50^a that the pressure in reservoir 45 is gradually reduced by a suitable amount, such as twenty pounds. The engineman then moves the brake valve P to the lap position to close all the ports of valve P. Brake pipe 25 pressure, applied to the underside of valve 43, moves this valve upwardly against the force exerted by the reduced pressure in chamber 42 above the valve. Brake pipe 3 is therefore vented to atmosphere through 30 vent pipe 44 and orifice 98 which is sufficiently restricted to create a back pressure in vent pipe 44. When the pressure in brake pipe 3 is reduced to a value slightly below the pressure existing in reservoir 45, valve 35 43 closes, and disconnects pipe 3 from vent pipe 44. This reduction in the pressure in brake pipe 3 of course applies the brakes. The back pressure created in pipe 44 is supplied to chamber 68 of relay valve K and 40 moves plunger 70 and valve 72 downwardly to disconnect pipe 74 from atmosphere and to connect this pipe with pipe 6. Pressure is therefore supplied through pipe 74, check valve 77, pipe 84, port 113 in valve S, pipe 45 114, port 92 in valve J, and pipe 54, to chamber 35 under diaphragm 33 of cut-out valve H. This pressure moves plunger 36 upwardly and disconnects pipe 4 from pipe 22. With valve H closed it is manifest that de-50 energization of valve D when valve E is open can have no effect upon the reduction valve S controlled by pipe 4. It should be here pointed out however, that if valve S has been reversed to cause an automatic brake application, pipe 84 will be disconnected from pipe 114, and valve H cannot operate as just described. The engineman must therefore commence the manual brake application prior to the reversal of valve S to 55 prevent an automatic application.

Actuation of relay valve K also supplies air pressure from pipe 6 through valve K, pipe 74, check valve 77, check valve 79, and restricted orifice 83 to reservoir 82, and this 60 reservoir is therefore charged with air pres-

sure to a degree which is substantially proportional to the length of time during which equalizing valve 43 is open. It should be pointed out that the reduction in brake pipe pressure caused by the opening of equalizing valve 43 is accomplished by venting the brake pipe to atmosphere through a restricted orifice. It follows that the length of time required to make a given reduction in the brake pipe of a train will be comparatively short for short trains and will be comparatively long for long trains because of the great difference in the volumes of air contained in the brake pipes in trains of different lengths. 70

The movement of valve P to the brake applying position also disconnects pipe 49 from brake pipe 3 and the pressure existing in the brake pipe before manual reduction is therefore trapped in pipe 49, reservoir 60 and chamber 59 under diaphragm 55 of valve G. When the pressure in the brake pipe, which is constantly connected with chamber 58 above this diaphragm, is reduced by a predetermined amount, such as twenty pounds, the pressure exerted on the underside of the diaphragm moves the diaphragm upwardly against the force exerted by the reduced brake pipe pressure. This motion of diaphragm 55 raises plunger 56 and valve 61 so that pipe 62 is then disconnected from the atmosphere and is connected with the brake pipe 3. Brake pipe pressure is therefore supplied through pipe 62, port 93 of repeater valve J, pipe 94 and restricted orifice 95 to chamber 88. This pressure is also supplied to the small reservoir 96. Because of the restricted orifice 95 the pressure in reservoir 96 increases faster than in chamber 88. After a brief time interval, during 90 which reservoir 96 becomes charged to a higher pressure than that existing in chamber 88, the pressure exerted in chamber 88, combines with the force exerted by spring 89, to move the piston 87 to the left against the pressure exerted in chamber 86 by pressure furnished thereto by supply pipe 6. As soon as this motion is commenced the piston 87 moves slide valve 90 to the left, disconnecting pipe 94 from pipe 62 but the movement is completed by the stored higher pressure in reservoir 96 and in its final position valve 90 connects pipe 94 with pipe 91. But pipe 91 is closed at the engineman's 95 brake valve P, and the pressure to which reservoir 82 has been previously charged is supplied to chamber 88 and serves to hold piston 87 in its left-hand position. The shifting of slide valve 90 of repeater valve J also disconnects pipe 54 from pipe 114 and connects pipe 54 with pipe 91 through port 92. The pressure in reservoir 82 is also supplied to chamber 35 of cut-out valve H and therefore holds plunger 36 of this valve in its upper position to disconnect pipe 100 105 110 115 120 125 130

- 4 from pipe 22. The closing of the equalizing valve 43 causes the back pressure in pipe 44 to be discontinued and so valve member 72 of relay valve K is moved to its upper position by spring 73. By this operation of relay valve K, pipe 74 is disconnected from supply pipe 6 and is connected with atmosphere through port 67^a. Although pipe 74 is opened to atmosphere, pressure in reservoir 82 is prevented from leaking off through this pipe by the check valve 79. The movement of the engineman's brake valve to the lap position has no effect on the remaining apparatus and valves G and H continue to be held in their upper positions and the slide valve 90 of repeater valve J is held in its left-hand position by piston 87. As long as valve H is closed so that pipe 4 is disconnected from pipe 22, the magnet valve D and the pin valve E can have no effect upon the valve S. If the engineman wishes to release the brakes he moves valve P to the release position, thereby connecting the brake pipe with pipe 6^a through port 48 and recharging the brake pipe. This operation of valve P, however, opens pipe 91 to atmosphere through port 50. The pressure in reservoir 82, which is now holding valve J in its left-hand position and is holding valve H closed is gradually dissipated to atmosphere through restricted orifice 97. After this pressure is sufficiently reduced valve H opens, connecting pipe 4 with pipe 22. It will be seen that the length of time required for valve H to open after the brake valve P is moved to the release position is proportional to the pressure to which the reservoir 82 was charged during the last preceding brake application and that this length of time is therefore proportional roughly to the length of the train. When initial brake pipe pressure is restored, valve G returns to its original position. Due to the restricted port 95 and to the volume of air contained in reservoir 96, piston 87 of valve J is held in its left-hand position for a time interval after valve H is restored, but when the pressure in this reservoir has been finally dissipated the pressure in chamber 86 returns piston 87 to the right-hand position and restores the apparatus to its initial condition. It will be seen that if, prior to the de-energization of valve D resulting from the entrance of the train into section B—C, the engineman has initiated a manual application of sufficient severity to bring the train below the speed limit imposed by the centrifuge L before the train reaches point C, the apparatus will permit the engineman to initiate a manual release of the brakes before the train is brought below this speed so that by the time the brake pipe is actually re-charged to a sufficient pressure to

release the brakes, the train will be below the speed limit. At this speed an automatic application of the brakes will not be incurred as the result of opening of valve D after valve H returns to its normal condition as the result of the reduction of pressure in reservoir 82 through restricted port 97. The advantage of this time element during which the release of the brakes may be initiated, prior to the time at which the train speed is brought below the speed limit, is due to the length of time required for the brake pipe pressure to be restored to the value required to release the brakes from the reduced value resulting from a brake application. The time interval required to release the brakes after the manual reduction varies with the length of the train for the same reasons as those pointed out in explaining the variable time interval required for a reduction in brake pipe pressure. With apparatus embodying my invention it will be plain that the engineman may initiate the release of the brakes, prior to an actual reduction in train speed below the limit imposed by centrifuge L, by a time which will enable the train speed to be brought within that speed limit by a brake application sufficiently heavy to actuate the differential valve G.

If the brake pipe reduction made by the engineman is of less than the amount necessary to actuate valve G, valve K will be operated, as before, to close valve H, but valve J will not be operated. When the engineman's brake valve P is moved to the lap position, therefore, valve K supplies pressure to chamber 35 of valve H as long as the brake pipe discharges through valve 43, but when this discharge ceases valve K moves upwardly and the pressure in chamber 35 slowly leaks off through pipe 54, port 92 of valve J, pipe 114, port 113 of valve S, pipe 84, restricted orifice 99, pipe 74, and port 67^a of valve K, to atmosphere. After a brief interval of time, therefore, valve H returns to its normal position, connecting pipe 4 with pipe 22. If, now, valves D and E are open, an automatic brake application will result. It will therefore be seen that a manual application of the brakes will not suppress an automatic application unless the manual application is of such amount as to cause valve G to operate.

I will now describe in detail how an automatic application of the brakes is accomplished by the reversal of reduction valve S. I will assume that all the parts are in the positions shown in the drawing. Under these conditions a reduction limiting reservoir 107 is connected with atmosphere through ports 116 and 117 of valve S, and the chamber 42 above the equalizing valve 43 is connected with reservoir 45 and with air pressure through pipe 108, port 109 in valve

S, pipe 110, port 100 in valve P, port 48 in valve P, feed valve 47, pipe 6^a, port 118 in valve S, and chamber 102 of valve S to pipe 6. Chamber 42 is also connected with the 5 brake pipe 3 through the same path as the one just traced to and including port 100, and from the latter port through the port in valve S leading to the brake pipe. The equalizing valve 43 is closed. I will now assume that valve D opens and that the speed 10 of the train is such that valve E is also open. Pipe 4 is therefore connected with atmosphere and valve S reversed as explained hereinbefore. Reservoir 107 is therefore 15 connected from atmosphere, and reservoir 45 is disconnected from pipe 110 and the two reservoirs 107 and 45 are connected together. The pressure in reservoir 45, and hence in chamber 42 above the equalizing 20 valve is therefore reduced by an amount which depends upon the relative volumes of the reservoirs. The parts are so proportioned that the resulting pressure decrease on reservoir 45 is enough to give a service 25 application of the brakes, as for example, a reduction of 20 pounds per square inch. This reduction in pressure in reservoir 45 is, of course, communicated to the chamber 42 above the equalizing valve, which therefore 30 rises, and connects the brake pipe 3 to atmosphere through vent pipe 44 and orifice 98. This connection reduces the pressure in pipe 3, and the pipe can not be recharged through the engineman's brake valve because 35 pipe 6^a is now blanked at valve S. The brake pipe pressure therefore drops and the brakes are applied.

The back pressure created in vent pipe 44 by the discharge of pipe 3 through the 40 restricted orifice 98 operates valve K so that air flows from pipe 6 into pipe 74. But this pressure cannot get into pipe 114 because port 113 of valve S is now closed. The pressure does build up in reservoir 82, however, 45 through valves 77 and 79 and restricted orifice 83. But if the engineman does not move his valve P to the lap position this pressure is dissipated to atmosphere through pipe 91 and the engineman's brake valve.

50 Assuming then that the engineman does move his brake valve P to the lap position as soon as the automatic application commences, the pressure supplied to reservoir 82 while the brake pipe is discharging through pipe 44 is trapped in reservoir 82 and pipe 91. The moving of valve P to the lap position blanks pipe 49, trapping in this pipe, and in reservoir 60, the initial brake pipe pressure. When the pressure in pipe 3 has been 55 reduced by a sufficient amount to operate valve G, pipe 62 is disconnected from atmosphere and connected with the brake pipe 3 as explained in connection with the operation of the apparatus under a manual application. Pressure thus supplied to pipe 62

flows through port 93 of valve J, to pipe 94. This pressure charges the small volume reservoir 96 and gradually builds up in chamber 88. After a time interval sufficient to fully charge the small volume reservoir 96, valve 70 J reverses, and pressure from reservoir 82 is supplied to pipe 94 through port 93, thus serving to maintain valve J in its reversed position. At the same time pressure from reservoir 82 flows through port 92, to pipe 75 54 and operates valve H to blank pipe 4.

It should be noticed that the reservoir 82 was charged through the orifice 83 as long as the brake pipe was discharging. It follows that the pressure in this reservoir depends upon the length of time necessary to make a predetermined brake pipe reduction. 80

After valve H closes, the pressure in chamber 103 of valve S starts to build up, and after a short time interval the valve 85 returns to its normal position, thereby re-connecting pipe 6^a with the source of fluid pressure and permitting the engineman to re-charge the brake pipe. As soon as valve P is moved to the release position however, 90 to charge the brake pipe, pipe 91 is connected to atmosphere, and the pressure in reservoir 82 is gradually dissipated through the orifice 97. When the pressure in the reservoir 82 is reduced below the value necessary to hold valve H closed, this valve opens, and unless the brake application resulting from the reversal of valve S has reduced the speed of the train below the value at which valve E will close, the opening of valve H will again vent pipe 4 to atmosphere and re-apply the brakes. If however, when valve H opens, valve E is closed, the pipe 4 is blanked and no application 95 of the brakes results. 100

When the pressure in chamber 88 is reduced below the value necessary to hold valve J in the reverse position, this valve returns to its normal position, and the return of valve G to its normal position, resulting from the reestablishing of brake 110 pipe pressure in pipe 3, returns the apparatus to its normal condition.

It follows that when the brakes have 115 been applied, either manually or automatically, the engineman may, by suitable manipulation of the brake valve P, initiate a release of the brakes prior to the actual reduction in train speed below the speed at which valve E opens by a time interval 120 which is proportional to the length of time required to make the reduction in brake pipe pressure.

Although I have herein shown and described only one form of train carried governing means embodying my invention, and only one form of train carried apparatus suitable for co-operation therewith, it is understood that various changes and modifications may be made therein within the 125 130

scope of the appended claims without departing from the spirit and scope of my invention.

Having thus described my invention, 5 what I claim is:

1. Railway traffic controlling apparatus comprising automatic apparatus on a train for applying the brakes, means effective when the brakes are being applied manually to render said automatic apparatus ineffective, and means effective when the brakes are being released to render said automatic apparatus ineffective for a time interval.
2. Railway traffic controlling apparatus comprising a brake pipe normally supplied with an initial fluid pressure and arranged to apply the brakes when such pressure is reduced, automatic means for applying the brakes, manually operable means for reducing the pressure in said brake pipe and arranged to render said automatic apparatus ineffective, means for restoring pressure to said brake pipe and means effective to render such automatic apparatus ineffective for a time interval the duration of which depends upon the time required to reduce the pressure in the brake pipe by a predetermined amount as a result of operation of said manually operable means.
3. Railway traffic controlling apparatus comprising means on a train for causing an automatic brake application, manually operable brake applying means effective when operated to render the automatic means ineffective to apply the brakes, and means for initiating a release of the brakes and effective for a time interval to render the automatic means ineffective to apply the brakes.
4. Railway traffic controlling apparatus comprising a brake pipe normally supplied with an initial fluid pressure and arranged to apply the brakes when such pressure is reduced, automatic means for applying the brakes, a reservoir, manually operable means for venting said pipe to atmosphere and for charging said reservoir with fluid pressure to a degree depending upon the time said brake pipe pressure is being reduced, means for restoring pressure to said brake pipe, and means operating while the pressure is being restored in said brake pipe and effective for a time interval the duration of which depends upon the degree to which said reservoir is charged to render said automatic apparatus ineffective to apply the brakes.

5. Railway traffic controlling apparatus comprising a brake pipe normally supplied with fluid pressure and arranged to apply the brakes when such pressure is reduced, a manually controlled brake valve and an equalizing valve for regulating the pressure in said brake pipe, a relay valve controlled by said equalizing valve, a pin valve for

causing an automatic application of the brakes if the speed of the train is above a predetermined value, a differential valve controlled by the pressure in the brake pipe, a repeater valve controlled by said differential valve and said relay valve, and a cut-out valve controlled by said repeater valve and by said relay valve for at times rendering said pin valve ineffective to apply the brakes.

6. Railway traffic controlling apparatus comprising a brake pipe normally supplied with fluid pressure and arranged to apply the brakes when the pressure in said pipe is reduced, a brake valve and an equalizing valve for controlling the pressure in said pipe, automatic means for applying the brakes, a relay valve controlled by said equalizing valve, and means controlled by said relay valve and by said brake valve for rendering such automatic means ineffective to apply the brakes.

7. Railway traffic controlling apparatus comprising a brake pipe normally supplied with initial fluid pressure and arranged to apply the brakes when such pressure is reduced, manually operable means for venting said pipe to atmosphere through a fixed orifice so that the pressure in said pipe is reduced by a given amount in a time which varies in accordance with the length of the train, automatic means for at times applying the brakes, means controlled by said manually operable means for rendering said automatic means ineffective to apply the brakes, and manually operable means for restoring pressure to said brake pipe and effective to render said automatic means ineffective to apply the brakes for a time interval the duration of which depends upon the length of time the brake pipe was last connected to atmosphere.

8. Railway traffic controlling apparatus comprising a brake pipe on a train normally supplied with fluid pressure and arranged to apply the brakes when such pressure is reduced, a manually operable brake valve, an equalizing valve controlled by said brake valve for at times connecting said brake pipe with atmosphere, a reservoir, a relay valve effective when said equalizing valve is open to charge said reservoir to a pressure which varies with the time such equalizing valve is open, automatic means for applying the brakes, means controlled by the brake valve for restoring pressure to said brake pipe and means operating when such pressure is being restored and effective for a time interval the duration of which depends upon the pressure to which said reservoir was charged prior to the operation of such restoring means for rendering said automatic means ineffective to apply the brakes.

9. Railway traffic controlling apparatus comprising automatic means on a train for

- causing a brake application, manual means for causing a brake application, and means effective after a manual or an automatic application for initiating a release of the 5 brakes and operating to render said automatic apparatus ineffective for a time interval the duration of which depends upon the time necessary to make a brake application of predetermined severity.
10. Railway traffic controlling apparatus comprising automatic means on a train for causing a brake application if the speed of the train is above a predetermined value, manual means for causing a brake application, and means effective after a manual or 15 an automatic application of the brakes for initiating a release of the brakes before the speed of the train is reduced by such application below said predetermined value and 20 operating to render such automatic means ineffective.
11. Railway traffic controlling apparatus on a train comprising a brake pipe normally charged with fluid pressure and means for applying the brakes if the pressure in said 25 pipe is reduced, manual means for connecting said brake pipe with a vent pipe communicating with atmosphere through a restricted orifice, automatic means for connecting said brake pipe with said vent pipe, 30 means for recharging the brake pipe, and means responsive to pressure in said vent pipe and operating when the brake pipe is being recharged to prevent operation of said automatic apparatus for a definite time 35 interval.
12. Railway traffic controlling apparatus on a train comprising a brake pipe normally charged with fluid pressure and means for applying the brakes if the pressure in said 40 pipe is reduced, manual means for connecting said brake pipe with a vent pipe communicating with atmosphere through a restricted orifice, automatic means for at times
- connecting said brake pipe with said vent pipe, means for recharging the brake pipe, 45 and means responsive to pressure in said vent pipe and operating when the brake pipe is being recharged to prevent operation of said automatic apparatus for a time interval.
13. Railway traffic controlling apparatus 50 comprising automatic means for causing a brake application if the speed of the train is above a predetermined value, and means for initiating a release of the brakes before the speed of the train is actually reduced below 55 said value and operating to render said automatic means ineffective for a time interval the duration of which depends upon the time during which said automatic means was operating.
14. Railway traffic controlling apparatus 60 comprising a brake pipe normally charged with fluid pressure and means for applying the brakes if such pressure is reduced, automatic means for connecting said brake pipe with atmosphere, and means under the control of the engineman for recharging said 65 brake pipe and operating to render such automatic means ineffective for a time interval the duration of which depends upon the length of time said brake pipe was connected with atmosphere.
15. Railway traffic controlling apparatus 70 comprising a brake pipe normally charged with fluid pressure and means for applying the brakes if such pressure is reduced, automatic means including a pipe 4 for connecting the brake pipe with atmosphere when pipe 4 is vented to atmosphere, means for at 75 times venting pipe 4 to atmosphere, and means under the control of the engineman for recharging the brake pipe, such last-mentioned means operating to blank pipe 4 for a time interval.

In testimony whereof I affix my signature.

HERBERT A. WALLACE.
